DESIGN FOR A FILE BOX FOR BUSINESS
CARDS OR SIMILAR ARTICLES

Glenn W. Periman, Los Angeles, Calif.

Application August 23, 1947, Serial No. 141,030

Term of patent 3½ years

(Cl. D58—11)

To all whom it may concern:

Be it known that I, Glenn W. Periman, a citizen of the United States and a resident of Los Angeles, California, have invented a new, original, and ornamental Design for a File Box for Business Cards or Similar Articles, of which the following is a specification, reference being had to the accompanying drawing, forming part thereof.

Referring to the drawing:

Figure 1 is a top perspective view of a file box for business cards or similar articles, showing my new design;

I claim:

The ornamental design for a file box for business cards or similar articles, as shown.

GLENN W. PERIMAN.
